RACK FOR CONDIMENTS HOLDERS OR SIMILAR ARTICLE

Paul D. McGee, Chicago, Ill., assignor to Superior Plastics Inc., Chicago, Ill., a corporation of Delaware

Application July 29, 1952, Serial No. 20,798

Term of patent 14 years

(Cl. D44—29)

To all whom it may concern:

Be it known that I, Paul D. McGee, a citizen of the United States, residing at Chicago, in the county of Cook and State of Illinois, have invented a new, original, and ornamental Design for a Rack for Condiment Holders or Similar Article, of which the following is a specification, reference being had to the accompanying drawing, forming part thereof:

Fig. 1 is a front elevational view of a rack for condiment holders or similar article, showing my new design.

Fig. 2 is a side elevational view.

Fig. 3 is a top elevational view.

Fig. 4 is a cross sectional view taken on the line 4—4 of Fig. 1.

The dotted line disclosures of condiment
holders in Figs. 1 and 2 are only for illustration purposes.

I claim:

The ornamental design for a rack for condiment holders or similar article, substantially as shown and described.

PAUL D. McGEE.
